UNITED STATES PATENT OFFICE

2,124,291

METHOD OF AIR CONDITIONING

Walter L. Fleisher, New York, N. Y.

Application April 1, 1935, Serial No. 14,067

3 Claims. (Cl. 257—1)

This application is a continuation, in part, of my copending application Serial No. 751,684, filed November 6, 1934, and which issued into Patent No. 2,105,882, Jan. 18, 1938.

5 The general object of the invention is to provide a heat exchanger coil arrangement for use in an air conditioning system which will enable a volume of air to be properly dehumidified under summer conditions without producing a final dry 10 bulb temperature and relative humidity too extreme for human comfort.

Another object is to provide a heat exchanger arrangement which will enable all air employed in an air conditioning system to pass through the 15 exchanger and emerge in a proper and predetermined condition without the use of mechanical reheaters.

Another feature covers the use of a cooling coil in a series arrangement in which different sections of the coil, crosswise of a casing, assume 20 different temperatures, the same conditioning medium flowing through all sections.

A further feature covers the use of a cooling coil in which different sections of the coil, both 25 lengthwise and crosswise of a casing, assume different temperatures, the same conditioning medium flowing through all sections.

These and other objects and features will be 30 more apparent from the following description of illustrative forms of applicant's exchanger arrangements, to be read in connection with the accompanying diagrammatic drawings, in which:

Fig. 1 is a perspective view illustrating diagrammatically a cooling coil arrangement in a 35 conditioning casing in which a plurality of coils, extending to different degrees crosswise of the casing, are arranged in parallel arrangement with respect to flow of conditioning medium to and from the coils;

40 Fig. 2 is a diagrammatic view in perspective of a modified arrangement of the coils in Fig. 1, in which the coils are in series with respect to flow of conditioning medium to and from the coils; and

45 Fig. 3 is a diagrammatic view in perspective of another modified coil arrangement.

Considering the drawings, similar numbers referring to similar parts, numeral 10 designates a casing through which air from any desired source 50 or sources flows impelled therethrough by a fan, not shown. Cooling coils 4, 5 and 6, in Fig. 1, are positioned crosswise of the casing. The coils may all be of the same or varying dimensions in diameter and character of radiating extended surfaces. Coil 6 extends across the whole width

of the casing, whereas coil 5 extends two-thirds across the casing, and coil 4 extends only one-third across. The three coils are supplied with refrigerant or refrigerated medium from a suitable source through supply pipe 7, the medium being returned to the refrigerating equipment through return line 8. As shown in Fig. 1, coils 4, 5 and 6 are arranged in parallel with respect to lines 7 and 8. Hence, the coils are all supplied with medium at the same temperature.

5 However, air in the stratum 19 indicated by the arrows in Fig. 1, will pass through the three coils, whereas air in stratum 20 will pass through two coils, and air in the stratum 21 will only pass in contact with coil 6. As a result, different air 15 volumes will be conditioned to different degrees and form a final mixture at a median temperature and relative humidity, suitable for introduction into an area to be conditioned.

In Fig. 2, coils 4, 5 and 6 are positioned in casing 10 in like manner as in Fig. 1, except that they are arranged in series with respect to lines 7 and 8. Thus, the medium in coil 5 will be at a different temperature, warmer than that of coil 4, under summer operating conditions; and the 25 medium in coil 6 will be still warmer. The air flows through the casing in the direction of the arrows and whereas the whole stream will contact with coil 6, only two-thirds will contact with coils 5 and 6 and only one-third with all three coils. 30 Applicant thus combines the counter-flow principle of heat exchange with his arrangement of coils extended different distances across a conditioner.

In Fig. 3, the arrangement of coils radically 35 departs from that of Figs. 1 and 2, and utilizes a plurality of coils arranged to form coil sections of different thicknesses in different cross-sectional portions of the casing. The piping arrangement, while in series, first traverses a series of 40 coils serving one stratum of an air stream, then traverses the series serving the adjacent stratum, and so on. While six coils are shown, any number, both lengthwise and crosswise may be arranged, to carry out the invention. In Fig. 3, the 45 medium supplied through line 7 first flows through coils 12, 13 and 14 in series, counter to the flow of air through the casing, then flows through middle coils 15 and 16, and finally, through coils 17 before discharging into return 50 line 8. As a result, the three coils serving stratum 22 are each at a different temperature, and the two coils serving stratum 23 are at different temperatures with respect to the first three coils, and also, with respect to each other and the coil 17 55

serving stratum 24 is at still a different temperature. A maximum heat exchange between conditioning medium and air stream to achieve a dehumidified condition but at a relatively comfortable dry bulb temperature and relative humidity is thereby brought about.

It is apparent that the arrangement of coils, lengthwise and crosswise of a casing, and in thickness, to different extent, and in combinations of series and parallel arrangements to suit varying requirements, is within the purview of this invention.

In the above description and in the accompanying claims, the expression "lengthwise of the casing" shall be understood to refer to distance through the casing measured parallel to air flow therethrough; the expression "crosswise of the casing" shall be understood to relate to distances measured at right angles to the direction of air flow; and the term "thickness" shall be understood to relate to measurements taken lengthwise of the casing.

I claim:

1. A method of conditioning air which consists, first, in passing conditioning medium in heat exchange relation with a first portion of an air stream, then in heat exchange relation with a second portion of an air stream and the first portion of the air stream, and then in heat exchange relation with the first portion of the air

stream, the second portion of the air stream and a third portion of the air stream.

2. A method of conditioning air which consists, first, in passing conditioning medium in heat exchange relation with a first portion of an air stream, then in heat exchange relation with a second portion of an air stream and the first portion of the air stream and then in heat exchange relation with the first portion of the air stream, the second portion of the air stream and a third portion of the air stream, the conditioning medium being passed in counter current heat exchange relation with the air stream.

3. The method of controlling the moisture content and temperature of air which consists in directing a stream of air through a passageway, passing one portion of said air stream in indirect heat exchange relation with a relatively large volume of conditioning medium, passing another portion of said air stream in indirect heat exchange relation with a smaller volume of conditioning medium which has been in heat exchange relation with said first-mentioned portion of the air stream, and passing a third portion of the air stream in indirect heat exchange relation with conditioning medium which has been in heat exchange relation with said first-mentioned and second-mentioned portions of said air stream.

WALTER L. FLEISHER. 30
